UNITED STATES PATENT OFFICE.

JOSEPH VAN ACKEREN, OF PITTSBURGH, PENNSYLVANIA, ASSIGNOR TO THE KOPPERS COMPANY, OF PITTSBURGH, PENNSYLVANIA, A CORPORATION OF PENNSYLVANIA.

COKING RETORT OVEN.

1,410,784.

Specification of Letters Patent. Patented Mar. 28, 1922.

Application filed April 27, 1920. Serial No. 377,024.

To all whom it may concern:

Be it known that I, JOSEPH VAN ACKEREN, a citizen of the United States, residing in Pittsburgh, in the county of Allegheny and 5 State of Pennsylvania, have invented a new and useful Improvement in Coking Retort Ovens, of which the following is a specification.

This invention relates to by-product coke 10 ovens, more especially to coking retort ovens of the well known Koppers cross-regenerative type exemplified in the patent to H. Koppers No. 818,033, dated April 17, 1906.

One of the principal objects of the invention 15 is the provision of a combination coking retort oven of the cross-regenerative type that may be rapidly converted for use alternatively as a gas oven and as a coke oven. That is to say the oven may be used as a coke 20 oven wherein the heat for coking the charges of coal is derived from the combustion of the coke oven gas evolved from the carbonization process within the coking chambers; or by the making of a simple adjustment, as will hereinafter appear, the oven 25 may be operated as a gas oven, during which operation the entire product of coke oven gas is saved and an extraneously derived special generator gas, for example producer gas, is 30 employed for heating the charges of coal in the coking chambers. The invention not only contemplates the quick and ready conversion of the oven for operation in one way or the other, as above specified, without the 35 adjustments hereinbefore encountered in the conversion of combination ovens, but also provides in each use of the oven, an air supply of a character necessary to meet the requirements of the fuel being burned and 40 effects this result without any additional apparatus or the necessity for complicated adjustment of the air supply.

In addition to the general objects recited 45 above, the invention has for its objects such other improvements or advantages in construction and operation as are found to obtain in the structures and devices hereinafter described or claimed.

In the accompanying drawings, forming 50 a part of this specification, and showing, for

purposes of exemplification, a preferred form and manner in which the invention may be embodied and practiced, but without limiting the claimed invention specifically to such illustrative instance or instances:

55

Figure 1 is a composite vertical sectional elevation through a coking retort oven of a type embodying features above specified and equipped with the improvements of the present invention, the view being taken on vertical planes crosswise of the coke oven through the heating wall and also through the coking chamber, as indicated by the line 1—1 of Figure 2, for the purpose of disclosing all the parts necessary for an understanding of the invention;

60

Figure 2 is a longitudinal section through a coking retort oven of the type illustrated in Figure 1;

65

Figure 3 is an enlarged detailed crosswise vertical section of the damper region of a coking retort oven, such as illustrated in Figures 1 and 2;

70

Figure 4 is a horizontal section on the line 4—4 of Figure 3;

75

Figure 5 is a longitudinal vertical section on the line 5—5 of Figure 3;

Figure 6 is a perspective of a damper brick.

The same characters of reference indicate 80 the same parts throughout the several views.

In its present embodiment, the invention is incorporated in a coking retort oven or coke oven battery provided with crosswise extending parallel heating walls constituted 85 of series of vertical flame or heating flues, elongated coking chambers intermediate the heating walls and parallel therewith and crosswise regenerators located at a lower level than the heating walls and the coking 90 chambers and parallel therewith. For convenience, the present description will be confined to this use of the invention; features of construction are, however, readily susceptible of other valuable applications and, consequently, it is manifest that the scope of the 95 invention is by no means confined to the specific use and specific embodiment herein described as an illustrative example.

Referring to the drawings, there are illus- 100

trated sectional views of a coke oven battery of the by-product type, such as has been hereinbefore mentioned, which embodies in its construction a plurality of crosswise elongated vertical heating walls 11—11 and a plurality of intermediate crosswise elongated vertical coking chambers or ovens 12—12, the latter alternating with the heating walls, as shown more particularly in Figure 2. The heating walls 11 form the side walls of the respective coking chambers 12 and are supported by the heavy supporting or pillar walls 13—13 extending crosswise of the battery, and in the present instance, beneath the heating walls 11, as particularly illustrated in Figure 2. These pillar walls collectively form the main support for the entire superstructure of the oven battery, and are themselves firmly supported upon a flat mat or platform 14, which constitutes the sub-foundation on which the entire battery rests.

The coal to be coked is charged into the several coking chambers or ovens 12 through suitable charging holes, not shown, but located in the usual manner in the top 15 of the oven battery and positioned directly above the ovens or coking chambers 12. Heat for coking the charges of coal in the several ovens or chambers 12 is derived from the heating walls 11, which, as before mentioned, extend crosswise of the battery at the sides of the coking chambers and are, in the present instance, each provided with a set of vertical heating or flame flues 16 constituting elongated chambers for the combustion of gaseous fuel in an atmosphere of highly preheated air. When the oven is used as a coke oven, the coke oven gas is supplied through gas conduits or channels 17, there being a gas channel for each set of heating flues. The several channels 17 extend lengthwise through the pillar walls 13 and communicate with the usual discharging ducts 18, indicated by dotted lines in Figure 5, such ducts individually extending to individual heating flues. After conversion of the oven into a gas oven, the special generator gas, such as produced gas, is introduced into the several heating flues of each heating wall in a manner which will hereinafter appear. The individual heating flues 16 of each set are connected by a horizontal flue 19 through which the products of combustion pass from those flues of each set which are operating for upflow to the flues of the same set on the other side of the coke oven which are operating for downflow. Above each heating flue 16 and adapted to communicate therewith through the horizontal flue is an access flue 20 extending to the top of the oven battery and adapted to be normally closed at its upper end by means of the usual cover plate.

Located at a lower level than the coking

chambers and the heating walls and positioned between each pair of adjacent pillar walls 13, is a pair of aligned crosswise-extending regenerators 21, the meeting ends of which are separated by the longitudinally extending partition 22, the latter dividing the oven longitudinally into two sections that operate according to the usual reversal principle fully set forth in the patent to Koppers above mentioned.

Each regenerator 21 is a chamber containing open brick work, commonly called checker work, and indicated at 23 with distributing sole channels 24, underneath such checker work, the channels forming the soles of such chambers and opening up into the 80 checker work; these regenerators in alternation are heated by the hot combustion products they draw off from the flame flues and then impart such heat to the medium that they feed directly into these flame flues when 85 the latter are burning.

In accordance with the invention, there is located in the top of each regenerator a horizontal partition 25 extending longitudinally with respect to the regenerator from the front to the inside end thereof. These partitions 25 serve to separate from the checker work of their respective regenerators, the regenerator spaces above such checker work; such regenerator spaces are themselves divided, by vertical partitions 26 extending lengthwise from end to end of the regenerators and connecting the soles of the oven chambers with the partitions 25, into individual and separated channels 27 also extending longitudinally within the top of their respective regenerators, there being two of such channels for each of the regenerators, with the exception of the regenerators at the end of the battery, as shown. These channels 27 are provided with ducts 28 leading respectively to the individual flame flues 16 of the sets of flame flues in the heating walls 11. In the arrangement shown, the ducts 28 of the two channels 27 of a regenerator respectively lead to the individual members of the sets of flame flues of the two adjacent heating walls 11 that are disposed next to and on the opposite sides of the regenerator beneath the coking chamber 12 between such heating walls. With this construction, it is possible to direct the entire flow from a regenerator through the ducts 28 of one channel 27 into the set of flame flues 16 of a single heating wall; or, on the other hand, it is possible to divide the flow from a regenerator so that part of the flow passes through one channel 27 and its ducts to the flame flues of one adjacent heating wall and the remainder of the flow passes through the 120 other channel 27 and its ducts into the flame flues of the next adjacent heating wall.

The invention provides a simple and easily

accessible means for regulating the flow from the checker work of the several regenerators, in order that the flow may be directed in either one or the other of the two courses set forth above. Near their front ends adjacent to the sides of the oven battery, the horizontal partitions 25 are respectively provided with two ports 29, said ports being located respectively on opposite sides of the vertical partition 26. For opening and closing these ports 29, there are provided sliding damper bricks 30 mounted on the horizontal partition 25 and adapted to be operated by handles 31 that extend through control boxes 32 beyond the side of the coke oven battery, all as shown more particularly in Figures 4 to 6 inclusive. By operating the sliding dampers 30 from the outside of the coke oven battery, the ports 29 of the two channels 27 above the checker work of each regenerator may be opened or closed to place either one or both of such channels in communication with the checker work of their respective regenerators. The flow from or to each regenerator is thus capable of direct control by the manipulation of a simple manually operable means positioned in a most accessible place on the outside of the battery.

The invention contemplates using this very simple control of the regenerator flow for quickly converting the oven from a coke oven in which coke oven gas is used for heating purposes, into a gas oven wherein a special generator gas, such as producer gas, is used for heating the charges of coal being coked. When operating as a coke oven, the ports 29 of one channel 27 of each regenerator are closed by moving the damper bricks 30 over them and the parts of the opposite channel on the same side of the several regenerators in the lengthwise order of the battery are open. The coke oven gas is turned on into the gas ducts 17 and the entire flow from each of the upflow regenerators passes through a single series of ducts 28 into single sets of flame flues, thereby providing the necessary acceleration of flow, but without increasing the volume of the air supply for the burning of the coke oven gas. The entire downflow also passes to each regenerator through a single series of ducts 28.

The acceleration of flow is such as to provide proper distention or lengthening of the coke oven gas flame within the flues, to avoid local flame concentration towards the bottom of such flues. On the other hand when operating with a special generator gas, such as producer gas, requiring only about one-fifth as much air per unit of gas volume but having an almost proportionately lower heat value, the air supply per unit of time must be about the same, but furnished from only half the number of regenerators. Both

ports 29 of all the regenerators are opened 65 by manipulation of the damper bricks 30, so that the flow from each regenerator is divided and passes into the flame flues of the pair of heating walls adjacent to such regenerators and the producer gas is introduced 70 into alternate regenerators and the air for supporting combustion is introduced into the regenerators intermediate such alternate regenerators. Each regenerator thus feeds two sets of heating flues and the producer 75 gas flowing into a set of heating flues from one regenerator meets the air flowing into the same flues from the adjacent regenerator. The volume of air required for the proper combustion of producer gas is greatly less 80 than that required for the coke oven gas and the divided flow from each regenerator insures the proper proportion of air and gas in each heating flue.

The conversion of the oven from a gas oven 85 into a coke oven or vice versa, provided by the present invention, may be made without the complicated adjustments heretofore encountered when converting combination ovens, because the mere damper regulation 90 itself provides the proper proportion of air and gas in burning either of the two kinds of gas. Moreover the control permitting the conversion of the oven is located exteriorly of the battery, thereby making it a simple 95 matter for an attendant to walk along the outside of the battery and adjust the dampers.

The invention as hereinabove set forth is embodied in a particular form of construction, but may be variously embodied within the scope of the claims hereinafter made.

What is claimed is:

1. A coking retort oven, having coking chambers, heating walls contiguous to such coking chambers and regenerators, combined with means for optionally effecting communication between a regenerator and the heating walls on both sides of a coking chamber or only with a single heating wall; substantially as specified.

2. In a coking retort oven, in combination: parallel coking chambers; heating walls contiguous to the coking chambers and parallel therewith; regenerators located at a lower level than the heating walls and the coking chambers and parallel therewith; and means for interchangeably connecting such regenerators each with a pair of adjacent heating walls or with a single heating wall; substantially as specified.

3. A coking retort oven having coking chambers, heating walls contiguous to such coking chambers and regenerators, combined with dampers individually associated with each regenerator for optionally effecting communication between a regenerator and the heating walls on both sides of a coking

chamber or only with a single heating wall; substantially as specified.

4. In a coking retort oven, in combination : parallel coking chambers; heating walls contiguous to the coking chambers and parallel therewith; regenerators located at a lower level than the heating walls and coking chambers and parallel therewith; and dampers individually associated with each 10 regenerator for interchangeably connecting such regenerators each with a pair of adjacent heating walls or with a single heating wall; substantially as specified.

5. In a coking retort oven, in combination : 15 coking chambers; heating walls contiguous thereto; regenerators located at a lower level than the heating walls and coking chambers, and respectively having in their tops two channels extending there along and individually communicating with individual heating walls; and means for interchangeably placing such channels singly or collectively in communication with the checker work of said regenerators; substantially as 25 specified.

6. In a coking retort oven, in combination : coking chambers; heating walls contiguous thereto and respectively provided with a set of heating flues; regenerators located at a 30 lower level than the heating walls and the coking chambers, and respectively having in their tops two channels extending there along and individually communicating by ducts with a set of flues of an individual 35 heating wall; and means for interchangeably placing said channels singly or collectively in communication with the checker work of said regenerators; substantially as specified.

7. In a coking retort oven, in combination : 40 coking chambers; heating walls contiguous to the coking chambers; regenerators; and

means for interchangeably connecting such regenerators each with a pair of heating walls or with a single heating wall; substantially as specified.

45

8. In a coking retort oven, in combination : coking chambers; heating walls contiguous thereto; regenerators located at a lower level than the heating walls and the coking chambers, and respectively having in their tops 50 two channels extending there along and individually communicating with individual heating walls; and dampers individually associated with each regenerator for interchangeably placing said channels singly or 55 collectively in communication with the checker work of said regenerators; substantially as specified.

9. In a coking retort oven, in combination : coking chambers; alternately disposed heating walls contiguous to the coking chambers and respectively provided with a set of heating flues; regenerators located at a lower level than the heating walls of the coking chambers and respectively provided with 60 two sets of ports, said sets of ports respectively leading to the sets of heating flues of a pair of adjacent heating walls; and means for interchangeably directing the regenerator flow through both or through one set of 65 such ports; substantially as specified.

10. A coking retort oven, having coking chambers, heating walls contiguous to such coking chambers, regenerators, and duct means interposed between a regenerator and 70 a pair of adjacent heating walls, combined with means for optionally directing the flow from a regenerator, through said duct means, into both said heating walls, or into only one of them; substantially as specified.
